United States Patent Office.

DAVID SHIVE, OF PHILADELPHIA, PENNSYLVANIA.

Letters Patent No. 64,717, dated May 14, 1867; antedated May 9, 1867.

IMPROVEMENT IN SWEAT-LEATHERS FOR HATS.

The Schedule referred to in these Letters Patent and making part of the same.

TO ALL WHOM IT MAY CONCERN:

Be it known that I, DAVID SHIVE, of the city of Philadelphia, in the State of Pennsylvania, have invented a new and useful Improvement in Hats; and I do hereby declare that the following is a full, clear, and exact description of the construction and operation of the same, reference being had to the accompanying drawings, making a part of this specification, in which—

Figure 1 is a plane view of the under side of a hat having my improvement applied thereto.

Figure 2, a vertical transverse section of fig. 1, showing a front view of the improvement applied; and

Figure 3, a vertical longitudinal section of fig. 2—

Like letters of reference indicating the same parts when in the different figures.

The sweat-leather of a man's hat is generally secured around the inside edge of the rim by means of stitches passing through the upper edge of the leather, and consequently in warm weather the outside band of the hat soon becomes soiled by the sweaty fluid from the forehead of the wearer passing through the said stitch-holes and the body of the hat; and to prevent this objectionable result is the object of my invention. It consists, substantially as hereinafter described, in the application of a supplementary sweat-leather, having a flapped edge made so that it will extend about half an inch, more or less, over on the rim of the hat, and retain its proper position without the stitching and consequent perforations heretofore required in the sweat-leather.

In the drawings, A is the body of a hat, a^1 its rim, a^2 its usual sweat-leather, and B the supplementary sweat-leather. The supplementary sweat-leather B has a flap, b^1 , and is applied to the front portion of a hat which has the usual sweat-leather a^2 previously stitched fast around within the rim a^1 , as heretofore. It is secured to the said leather a^2 by cementing a portion of its inner side b^2 fast to the leather a^2 , and with its flapped edge b^1 extending over upon and fitting loosely but closely down upon the rim a^1 of the hat; the flat b^1 being formed or "laid" by pressing the edge of the leather down upon the rim a^1 , so as to cause it to lie closely and evenly, substantially as shown. It will be seen that as the flap b^1 is simply a continuation of the piece of leather B, extending over and covering the stitched edge of the usual sweat-leather a^2 , and over about the width of half an inch of the rim a^1 , without any perforations whatever, the sweaty fluid from the forehead of the wearer will be prevented from passing through the body of the hat, thus protecting the usual outside band from being soiled thereby.

I do not intend to limit the supplementary sweat-leather B to the front or forehead portion of the hat, but to extend it entirely around in the same manner, should it be found desirable.

Having thus fully described my improvement, what I claim as new, and desire to secure by Letters Patent, is—

The application to a hat of the supplementary sweat-leather B, constructed and operating substantially as and for the purpose described.

DAVID SHIVE.
